UNITED STATES PATENT OFFICE.

FRANK W. CALDWELL AND JOHN C. MORSE, OF DAYTON, OHIO.

METHOD OF TIPPING AIRCRAFT PROPELLERS.

Application filed October 11, 1921. Serial No. 506,983.

To all whom it may concern:

Be it known that we, FRANK W. CALDWELL and JOHN C. MORSE, citizens of the United States, residing at Dayton, in the county of Montgomery and State of Ohio, have invented certain new and useful Improvements in Methods of Tipping Aircraft Propellers, of which the following is a specification.

10 Our invention relates to an improved protective covering or tipping for propeller blades and the edges and tips thereof.

Considerable difficulty has been experienced with the boot type of tipping heretofore used as a protective covering for airplane propellers owing to the cracking and breaking of the metal composing the same, with the result that parts of the covering or the whole boot-like tipping has been thrown 20 off the propeller.

Our invention aims to overcome this difficulty by providing a sheathing or tipping formed from a continuous sheet of metal fabric or other suitable material which is applied to the tip, and along the leading edge of the blade and supplemented at the tip by a small piece of like material. The covering or tipping is cut from a sheet of suitable material, preferably metal, which is then notched on opposite sides so as to form a narrow, continuous central strip having a plurality of spaced segments extending laterally therefrom, and a plain portion at one end adapted to partially embrace the tip 35 of the blade.

In applying the tipping to a propeller blade the central strip is bent over the leading edge and the segments contact with and follow the contour of opposite faces of the 40 blade. Each segment is firmly secured to the blade so that even a crack extending through the central strip between opposite notches would do no harm. In fact, should one of the small sections formed by several 45 of such cracks happen to fly off, it would not greatly unbalance the propeller.

Furthermore this improved protective covering, because of its flexibility, does not in any way restrain the movements of the 50 propeller.

The invention is described in the following specification in connection with the accompanying drawings, in which:

Figure 1 is a plan view of the tipping as 55 cut from the sheet metal and notched.

Figure 2 is a plan view of the small supplemental end piece.

Figure 3 shows the manner in which the tipping is applied to a propeller blade.

Figure 4 is a side elevation of a propeller 60 blade having our improved tipping applied thereto.

As shown in Figure 1, the tipping is cut from a metallic strip so as to form an end piece 10 adapted to extend across one face, 65 and have its edges bent over the edges of the blade 11, at the tip thereof. The body of the sheathing is notched on opposite sides, as shown at 12, in order to form a series of spaced segments or projections 13 which 70 may be of curved, irregular, or polygonal form as desired. These segments 13 extend from opposite sides of a central continuous strip 14 which is integral with the end piece 10 and projects therefrom at one side of the 75 longitudinal axis of the latter.

The tipping is applied to a propeller blade in such manner that the continuous strip 14 is bent over the leading edge and the segments 13 contact with opposite faces of the 80 blade. In Figure 2, a small end piece 15 is illustrated which is adapted to be applied at the tip of the blade across the face opposite from the end piece 10. The edges 16 of the end piece 10 are bent over the edges and 85 tip of the blade and overlap the small piece 15. In order not to have a ridge where the metal is thus overlapped, the metal should be filed to a knife edge along the edge of the under piece as well as along the edge of the 90 overlapping piece. The end pieces are preferably secured to the propeller blades by means of rivets 17 so as to form a sort of a cap for receiving the tip of the propeller. The segments 13 are bent to conform to the 95 contour of the blades and are secured thereto by means of screws 18.

The screw and rivet heads as well as the seam of the cap are subsequently covered with solder. The solder is then cleaned off 100 level with the metal of the sheathing so as to present a smooth exterior. Several small holes 20, usually three in number, are drilled through the tipping at the extreme tip 19 to allow any moisture that may be forced under the tipping to escape under the influence of centrifugal force. The propeller should be balanced before enamelling but if the tipping has been carefully applied the propeller is usually nearly in balance. 105 110

Our improved tipping is light and flexible but practical tests have demonstrated that it affords good protection to the leading edge and tip of a propeller blade.

5. We have shown and described one form of our invention in order to set forth the precise invention and explain the principle thereof, but it will be understood that it is not our intention to limit the scope of the invention to the disclosure, except as may be required by the appended claims.

Having thus described our invention, we claim:

1. The combination with a propeller blade, of tipping therefor comprising a continuous strip embracing an edge of the blade, and spaced segments extending from opposite sides of said strip adapted to be secured to said blade.

2. The combination with a propeller blade, of tipping therefor comprising a continuous sheet of material having a series of notches therein forming a plurality of laterally projecting spaced segments.

3. The combination with a propeller blade, of tipping therefor comprising a sheet of material having an end piece adapted to be secured at the tip of the propeller, a continuous strip extending from said end piece and adapted to be bent over the leading edge of the blade, and spaced segments projecting laterally from said strip.

4. The combination with a propeller blade, of tipping therefor comprising a sheet of material having an end piece adapted to partially embrace the tip of the propeller, a continuous strip extending from said end piece and adapted to be bent over the leading edge of the blade, means for se-

curing said strip to the blade, a supplemental end piece for forming with said first named end piece a cap adapted to receive the tip of the blade, a plurality of apertures at the edge of said supplemental end piece for the purpose described.

5. The combination with a propeller blade, of tipping therefor comprising a sheet of material having an end piece adapted to be applied to the tip of the blade, a strip extending from said end piece adapted to embrace an edge of the blade, and spaced segments projecting from said strip bendable to conform to the contour of the faces of said blade.

6. A tipping for propeller blades comprising a sheet of material having a series of notches cut therein for forming a row of spaced segments.

7. A tipping for propeller blades comprising a sheet of material having a continuous strip, and a plurality of spaced segments projecting laterally therefrom.

8. A tipping for propeller blades comprising a sheet of material having a continuous strip, a plurality of spaced segments projecting laterally from said strip, and an end piece integral with said strip adapted to engage the tip of the propeller blade.

9. A tipping for a propeller blade comprising an end cap for receiving the tip of the blade, a strip extending from said cap, and a plurality of spaced segments projecting laterally from said strip.

In testimony whereof we have affixed our signatures.

FRANK W. CALDWELL.
JOHN C. MORSE.
